METHOD OF MANUFACTURING HOLLOW
ARTICLES FORMED OF FLEXIBLE STRIP
MATERIAL

Edouard Louis Diet, Neuilly-sur-Seine, France

Application January 8, 1935, Serial No. 909. Renewed July 25, 1938. In France April 30, 1934

13 Claims. (Cl. 93—39.1)

The present invention relates to the manufacture of objects of hollow form having at least one tapered or contoured portion by means of a ribbon or strip of flexible material, paper, cardboard or the like, wound helicoidally on a mandrel of a corresponding shape.

According to the method of manufacture which forms the object of the present invention, there is employed as the ribbon or strip for forming the hollow body, a ribbon or strip having corrugations in a transverse direction with reference to its length and on its whole width; the said corrugations are substantially arranged over all the length of the strip to be wound on the tapered or contoured portion of the mandrel; so, one edge of the said strip is able to be more or less elongated relatively to the other during the winding of the said strip on the tapered or contoured portion of the mandrel; in these conditions, the successive helical turns of the strip are wound flat one upon another along the mandrel from one of the ends of the article to be made to the other; at the same time, they are joined together by any known means such as an adhesive material, glue or the like provided on one part of the width of the inner face of the ribbon or strip.

In this way, without drawing out the fibres of the material constituting the ribbon, in other words, without modifying the internal texture of this ribbon, it is possible to make hollow bodies of conical or any desired profile, and in a simple and rapid manner.

With a strip or ribbon of the above kind having transverse corrugations on its whole width, such as creped material, e. g. creped paper, the tension given to the strip or ribbon for its correct winding on the mandrel, and the application of the ribbon to all the conical or contoured part of the mandrel, suffices to produce the elongation of the corrugations necessary for making the contoured part to be obtained; in the various parts of the width of the strip or ribbon this elongation has the desired amplitude.

By employing the method above defined, it becomes possible to manufacture hollow bodies other than cylinders, and notably, bodies of revolution, of truncated conical form, or the generatrix of which is a curved line like the profile of a bottle.

At each of its ends this receptacle may be closed by any suitable means. For example, its end of larger diameter may be provided with a stamped or pressed bottom; this bottom is engaged in the receptacle to the desired extent and then it is crimped. A capsule placed on the end of the small diameter of the receptacle completes

the closure of the latter. This capsule may then be sealed in any desired manner.

According to one particular mode of carrying out the present invention, one of the ends of the lateral wall of the receptacle may comprise, for its manufacture, a sleeve for supporting the turns of this part of the winding. This sleeve is first placed on the forming mandrel and the winding is commenced on this sleeve, the primary turns being glued or otherwise fixed on it. This sleeve facilitates the formation of the side wall of the article and strengthens this wall.

According to the present invention, also, when employing a sleeve for the formation of the end of the wall of the receptacle situated toward the small base, the sleeve may be constituted by a stamped piece having a solid bottom which then forms the closure member for that end of the receptacle. This bottom is then first mounted on the mandrel; the free end of the ribbon or band for forming the article is fixed, for instance, by glueing to the side wall of the bottom at any desired point from the wall, and the winding of the ribbon is done up to the large base of the article to be made. If this article is intended to be filled, and is a bottle, for instance, its filling is effected by its large open base, which can then be closed, as before, by means of a bottom stamped and crimped.

According to the present invention, also, the ribbon employed for making the articles may be of a transparent or translucent material, so as to allow the material with which the receptacle may be subsequently filled, such as a liquid, when the article is a bottle, to be seen from the outside.

As already said, the successive turns or convolutions of the ribbon are joined together, the ribbon being provided on one part of the width of its inner face with an adhesive material, such as glue or the like.

In all cases, once the receptacle is formed and before filling, if it has to be filled, it may be provided internally with a suitable lining, for example, an impermeable lining, consisting for instance, of a film or coating of paraffin wax. It may also be treated externally in any desired manner.

In the accompanying drawing, which is given by way of example, and does not in any way limit the scope of the present invention:

Figure 1 is a front view, on a large scale, of a crimped ribbon employed for the manufacture of hollow contoured bodies like those above defined.

Figure 2 is a longitudinal section through the said ribbon.

Figure 3 is a front view of the same ribbon as it has been deformed in the course of its application to the contoured part of a mandrel for forming an article like that in Figures 4 and 5.

Figure 4 shows, on a reduced scale, an elevation of a paper bottle made according to the invention.

Figure 5 is a vertical axial section through the said bottle.

Figure 6 shows an arrangement for forming and closing the neck of a bottle similar to the preceding one.

In the various figures, the same reference numerals designate the same elements.

Referring to Figures 1 and 2, 1 is a ribbon or band serving for the making of hollow bodies in accordance with the invention. This ribbon has undulations or corrugations 2 which may be of any desired amplitude, so as to enable it to be elongated by pulling on it, or rather by deforming it so as to make it take an arcuate form, as in Figure 3 by exerting, for example, a greater pull on its edge 4 than that exerted on its opposite edge 3. With such a ribbon fixed or gripped by one of its ends on the end of the smaller diameter of a mandrel having the shape of the article to be made, it is possible, either by communicating a rotary movement to this mandrel, or by rotating the said ribbon about the mandrel, to wind this ribbon on the mandrel from the small base of the mandrel to its large base in such a manner as to obtain an article 5 of the shape shown in Figure 4. This figure shows that the article has a shoulder part 6-6, a cylindrical part 7, and a reinforcing member at each of its ends, namely, a reinforcing member 8 for the neck of the bottle, and another 9 for the bottom of the latter each of said reinforcing members may be made by circular turns of the strip or ribbon.

When forming the narrow part of the article 5 that is, when forming the cylindrical neck 8, the ribbon is circularly wound on the mandrel and consequently merely a uniform tension over all its width. Each of its edges 3 and 4 undergoes no deformation relative to the other; on the contrary, when forming the contoured part 6, the edge of the ribbon 3 situated towards the small base of the mandrel is subjected to less traction than the opposite edge 4 on the side towards the large base of the mandrel. This edge 4 therefore undergoes an elongation relative to the edge 3. Under these conditions the corrugations 2 of the ribbon are deformed, elongated and flattened out towards the edge 4. The deformation of the ribbon is effected automatically, in a greater or less degree, under the action of the variable traction to various points in its width and due to the contour of the mandrel; at each point in the width of the ribbon the traction depends on this contour. The turns or convulsions of the ribbon thus automatically deformed, wind themselves flat one upon the other, forming progressively the lateral wall of the article to be made (Figures 4 and 5).

As hereinabove stated, the reinforced end part 9 can be formed by winding the ribbon upon itself a number of times circularly instead of helically, the circularly coiled ribbon being continuous with the helically coiled ribbon.

As shown in Figure 5, once this lateral wall is made, it may be provided with a bottom 10, formed by a piece stamped from cardboard or like material, the flange 11 of which can be

turned towards the lower edge of the piece 5. This edge is then compressed internally by crimping at 12 on the side wall 11 of the bottom 10. A capsule 13 may then be placed on the neck 8 and held thereon in any suitable manner, for instance, by an impervious membrane of "Cellophane" or other suitable material affixed in any known manner.

As has been stated, according to one particular mode of carrying out the invention, a sleeve 14 of paper, cardboard or the like (Figure 5) may first be placed on the mandrel for forming the bottle, at one of the ends of this mandrel. The ribbon 1 is then fixed at its free end on this sleeve 14 by glueing, for example. The winding of the ribbon is then done and continued from the end of this sleeve 14 which is to constitute the small base of the article up to the opposite end of the mandrel, that is to say, until the completion of the visible side wall 5 (Figure 5). To facilitate the removal of this article from the mandrel, the latter may be divided, from one end to the other, into two or more parts, on a diametral plane or radial planes, these parts being, for instance, hinged to each other at the small base or end of the mandrel, so as to permit them to be slightly approached together when the making of each article is finished.

As already stated, a stamped end piece 15 made integral with the sleeve 14 may be employed for the formation of the side wall 5 (Figure 6). This end-piece 14-15 is mounted on the small base of the mandrel so as to cap it. The free end of the ribbon 1 for forming the article is fixed at a point 16 on this end-piece (Figure 6) so as to leave visible a length h of this end-piece, and the winding of the ribbon is performed as before, the various parts 8, 6, 7, 9, of the wall 5 being formed successively. When the winding is finished, the hollow article obtained is automatically closed at its end of smaller diameter, by the end-piece 15. It only remains, after having filled the bottle 5 to close it at its opposite end by the aid of a bottom-piece 10-11 like that in Figure 5. The filling of the bottle 5 is done, of course, by reversing the bottle and introducing the liquid from the large end 9. The stamped bottom 10 is, after the filling, fixed on the bottle 5 by crimping at 12 the end 9 of the bottle.

To empty the sealed bottle thus obtained, it suffices to pierce two holes 17 and 18 in the end-piece 15, one serving for the entry of air, and the other for the discharge of the liquid.

It will be understood that the modes above indicated of making shaped objects are given only by way of example.

In the drawing, 19 indicates an impervious lining applied to the internal face of the hollow article 5, this lining being formed, for example, by a layer of paraffin wax.

The outer surface of the articles manufactured as above may also be coated, printed, decorated, etc.

The ribbon employed for the formation of hollow articles of the type above defined may also be a smooth ribbon of paper, cardboard, etcetera; in that case, before its winding on the mandrel, or even during its unwinding from the reel, it is corrugated on all or part of its width.

For example, this crimping of the ribbon may be done by passing it between two cylindrical milling or knurling tools, whose teeth produce corrugations equivalent to those of the creping of the ribbon in Figures 1 and 2.

By selecting the dimensions of the milling teeth so that the ribbon may be subsequently deformed in the same way as the creped ribbon of Figures 1 and 2 as it is being wound on to the mandrel one can obtain, with the ribbon thus crimped in the course of its unwinding, articles of similar form to those obtained with the creped ribbon of Figures 1 and 2.

As has been hereinbefore indicated, instead of crimping, a smooth ribbon uniformly over all its width, this ribbon may be directly brought, by crimping between conical milling tools for example, to the form shown in Figure 3 corresponding to the maximum deformation that the ribbon has to undergo during its winding. In this way, when forming parts of the article to be made that are cylindrical or little contoured, the ribbon will automatically undergo an inverse deformation, bringing it wholly or partly back to its original state.

Thanks to the method above defined, receptacles may be made under particularly remarkable conditions of manufacture, which make possible the manufacture of such receptacles intended only to be used once, in the case of milk bottles, for instance, these receptacles being then thrown away when their contents are emptied.

It is to be noted that, especially in cases where these receptacles are used for holding liquids, they have the property of offering a remarkable resistance to shocks, owing to the special flexibility of their wall, due both to the nature of the material, paper, cardboard, etc., of which the wall consists, and on the other hand to the corrugations of the ribbon from which the wall of these receptacles is made.

This advantage is particularly valuable where the receptacles are filled with liquid, for instance milk, and are subjected to handling that is not always done with the gentleness desirable.

It is to be understood that in the following claims, the expression "contoured portion" means any portion other than a cylindrical portion, such as a tapered or conical portion, or a portion of any curved profile.

Having now particularly described and ascertained the nature of my said invention and in what manner the same is to be performed, I declare that what I claim is:

1. A method of making hollow articles having cross-sections of different sizes which consists in winding helically on a mandrel of corresponding shape a strip of flexible material having, on the whole of the length to be wound on any contoured part of the mandrel, transverse corrugations that have substantially the same value throughout the width of the strip, setting the said strip during its winding on any contoured part of the mandrel in such a manner that its longitudinal edge in front of the cross-section of the mandrel which is larger than the cross-section of the mandrel situated in front of the other longitudinal edge of the strip is elongated with reference to its original length and the length of this latter edge, the successive helical turns of the strip being thus wound flat one upon another along the mandrel from one end to the other during the winding and joined together, and then removing from the mandrel the article thus obtained.

2. A method of making hollow articles having cross-sections of different sizes which consists in winding helically on a mandrel of a corresponding shape a strip of a flexible material transversely creped at least on the whole

of the length to be wound on any contoured part of the mandrel, setting the said strip during its winding on any contoured part of the mandrel in such a manner that its longitudinal edge in front of the cross section of the mandrel which is larger than the cross-section of the mandrel situated in front of the other longitudinal edge of the strip is elongated with reference to its original length and the length of this latter edge, the successive helical turns of the strip being thus wound flat one upon another along the mandrel from one end to the other during the winding and joined together, and then removing from the mandrel the article thus obtained.

3. A method of making hollow articles having cross-sections of different sizes which consists in winding helically on a mandrel of a corresponding shape a strip of paper transversely creped at least on the whole of the length to be wound on any contoured part of the mandrel, setting the said strip during its winding on any contoured part of the mandrel in such a manner that its longitudinal edge in front of the cross-section of the mandrel situated in front of the other longitudinal edge of the strip is elongated with reference to its original length and the length of this latter edge, the successive helical turns of the strip being thus wound flat one upon another along the mandrel from one end to the other during the winding and joined together, and then removing from the mandrel the article thus obtained.

4. A method of making hollow articles having cross-sections of different sizes which consists in winding helically on a mandrel of a corresponding shape a strip of flexible material having on the whole of the length to be wound on any contoured part of the mandrel, transverse corrugations that have substantially the same value throughout the width of the strip, setting the said strip during its winding on any contoured part of the mandrel in such a manner that its longitudinal edge in front of the cross-section of the mandrel which is larger than the cross-section of the mandrel situated in front of the other longitudinal edge of the strip is elongated with reference to its original length and the length of this latter edge, the successive helical turns of the strip being thus wound flat one upon another along the mandrel from one end to the other during the winding, at least one circular turn of the strip being made at least one of the ends of the mandrel, each turn of the strip being joined to the previous one, and then removing from the mandrel the article thus obtained.

5. A method of making hollow articles having cross-sections of different sizes which consists in mounting a sleeve on the free end of a mandrel the shape of which corresponds to that of the article to be obtained, fixing on the said sleeve one of the ends of a strip of flexible material having, at least, on the whole length to be wound on any contoured part of the mandrel, transverse corrugations that have substantially the same value throughout the width of the strip, winding helically the said strip on the said sleeve and then on the mandrel by setting the said strip during its winding on any contoured part of the mandrel in such a manner that its longitudinal edge in front of the cross-section of the mandrel which is larger than the cross-section of the mandrel situated in front of the other longitudinal edge of the strip is elongated with

reference to its original length and the length of this latter edge, the successive helical turns of the strip being thus wound flat one upon another along the mandrel from one end to the other during the winding and joined together, and then removing from the mandrel the article thus obtained.

6. A method of making containers having cross-sections of different sizes which consists in mounting a piece having a bottom provided with a flange on the free end of a mandrel the shape of which corresponds to that of the containers to be obtained, fixing on the said flange one of the ends of a strip of flexible material having at least on the whole length to be wound on any contoured part of the mandrel, transverse corrugations that have substantially the same value throughout the width of the strip, winding helically the said strip on the said flange and then on the mandrel by setting the said strip during its winding on any contoured part of the mandrel in such a manner that its longitudinal edge in front of the cross-section of the mandrel which is larger than the cross-section of the mandrel situated in front of the other longitudinal edge of the strip is elongated with reference to its original length and the length of this latter edge, joining each turn of the strip to the previous one, the successive helical turns of the strip being thus wound flat one upon another along the mandrel from one end to the other, and then removing from the mandrel the article thus obtained.

7. A method of making containers having cross-sections of different sizes which consists in mounting a piece having a bottom provided with a flange and the free end of a mandrel the shape of which corresponds to that of the containers to be obtained, fixing on the said flange one of the ends of a strip of flexible material having at least on the whole length to be wound on any contoured part of the mandrel, transverse corrugations that have substantially the same value throughout the width of the strip, winding helically the said strip on the said flange and then on the mandrel by setting the said strip during its winding on any contoured part of the mandrel in such a manner that its longitudinal edge in front of the cross-section of the mandrel which is larger than the cross-section of the mandrel situated in front of the other longitudinal edge of the strip is elongated with reference to its original length and the length of this latter edge, joining each turn of the strip to the previous one, the successive helical turns of the strip being thus wound flat one upon another along the mandrel from one end to the other and at least, one circular turn of the strip being made at, at least, one of the ends of the mandrel, and then removing from the mandrel the article thus obtained.

8. A method of making hollow articles having cross-sections of different sizes which consists in winding helically on a mandrel of corresponding shape a strip of flexible material having on the whole length to be wound on any contoured part of the mandrel, transverse corrugations that have substantially the same value throughout the width of the strip, providing the said strip during the said winding with an adhesive coating on one part of the width of its inner face which is nearest the small end of the mandrel and setting the said strip during its winding on any contoured part of the mandrel in such a manner that its longitudinal edge in front of the cross-section of the mandrel which is larger than the cross-section of the

mandrel situated in front of the other longitudinal edge of the strip is elongated with reference to its original length and the length of this latter edge, the successive helical turns of the strip being thus wound flat one upon another along the mandrel from one end to the other and joined together by means of the said adhesive coating, and then removing from the mandrel the article thus obtained.

9. A method of making containers having cross-sections of different sizes which consists in winding helically on a mandrel the shape of which corresponds to that of the containers to be obtained a strip of flexible material having at least on the whole length to be wound on any contoured part of the mandrel, transverse corrugations that have substantially the same value throughout the width of the strip, setting the said strip during its winding on any contoured part of the mandrel in such a manner that its longitudinal edge in front of the cross-section of the mandrel which is larger than the cross-section of the mandrel situated in front of the other longitudinal edge of the strip is elongated with reference to its original length and the length of this latter edge, the successive helical turns of the strip being thus wound flat one upon another along the mandrel from one end to the other and at least one convolution of the strip being made with a nil pitch at, at least, one of the ends of the mandrel, then removing from the mandrel the article thus obtained, and providing the said article with a bottom at one of its ends.

10. A method of making containers having cross-sections of different sizes which consists in mounting a sleeve on the free end of a mandrel the shape of which corresponds to that of the containers to be obtained, fixing on the said sleeve one of the ends of a strip of flexible material having, at least, on the whole length to be wound on any contoured part of the mandrel, transverse corrugations that have substantially the same value throughout the width of the strip, setting the said strip during its winding on any contoured part of the mandrel in such a manner that its longitudinal edge in front of the cross-section of the mandrel which is larger than the cross-section of the mandrel situated in front of the other longitudinal edge of the strip is elongated with reference to its original length and the length of this latter edge, the successive helical turns of the strip being thus wound flat one upon another along the mandrel from one end to the other and at least, one convolution of the strip being made with a nil pitch at, at least, one of the ends of the mandrel, then removing from the mandrel the article thus obtained, and providing the said article with a bottom at one of its ends.

11. A method of making containers having cross-sections of different sizes which consists in mounting a piece having a bottom provided with a flange on the free end of a mandrel the shape of which corresponds to that of the containers to be obtained, fixing on the said flange one of the ends of a strip of flexible material having, at least, on the whole length to be wound on any contoured part of the mandrel, transverse corrugations that have substantially the same value throughout the width of the strip, winding helically the said strip on the said flange and then on the mandrel by setting the said strip during its winding on any contoured part of the mandrel in such a manner that its longitudinal edge in front of the cross-section of the mandrel which is larger than the cross-section of the mandrel situated in front of the other longitudinal edge of the strip is elongated with reference to its original length and the length of this latter edge, the successive helical turns of the strip being thus wound flat one upon another along the mandrel from one end to the other and at least, one convolution of the strip being made with a nil pitch at, at least, one of the ends of the mandrel, then removing from the mandrel the article thus obtained, and providing the said article with a bottom at one of its ends.

gated with reference to its original length and the length of this latter edge, joining each turn of the strip to the previous one, the successive helical turns of the strip being thus wound flat one upon another along the mandrel from one end to the other and at least, one convolution of the strip being made with a nil pitch at, at least, one of the ends of the mandrel, and then removing from the mandrel the container thus obtained.

12. A method of making containers having cross-sections of different sizes which consists in mounting a piece having a bottom provided with a flange on the free end of a mandrel the shape of which corresponds to that of the containers to be obtained, fixing on the said flange one of the ends of a strip of flexible material having at least on the whole length to be wound on any contoured part of the mandrel, transverse corrugations that have substantially the same value throughout the width of the strip, winding helically the said strip on the said flange and then on the mandrel by setting the said strip during its winding on any contoured part of the mandrel in such a manner that its longitudinal edge in front of the cross-section of the mandrel which is larger than the cross-section of the mandrel situated in front of the other longitudinal edge of the strip is elongated with reference to its original length and the length of this latter edge, joining each turn of the strip to the previous one, the successive helical turns of the strip being thus wound flat one upon another along the mandrel from one end to the other and, at least, one convolution of the strip being made with a nil pitch at, at least, one of the ends of the mandrel, then removing from the mandrel the container thus obtained, filling the said article through its open end, providing the said open end with a bottom having a flange turned towards the outer edge of the said open

end, crimping the said outer edge over the said flange and setting the said crimped edge against the said flange.

13. A method of making containers having cross-sections of different sizes which consists in mounting a piece having a bottom provided with a flange on the free end of a mandrel the shape of which corresponds to that of the containers to be obtained, fixing on the said flange one of the ends of a strip of flexible material having at least on the whole length to be wound on any contoured part of the mandrel, transverse corrugations that have substantially the same value throughout the width of the strip, winding helically the said strip on the said flange and then on the mandrel by setting the said strip during its winding on any contoured part of the mandrel in such a manner that its longitudinal edge in front of the cross-section of the mandrel which is larger than the cross-section of the mandrel situated in front of the other longitudinal edge of the strip is elongated with reference to its original length and the length of this latter edge, joining each turn of the strip to the previous one, the successive helical turns of the strip being thus wound flat one upon another along the mandrel from one end to the other and, at least, one convolution of the strip being made with a nil pitch at, at least, one of the ends of the mandrel, then removing from the mandrel the container thus obtained, providing one, at least, of outer or inner sides of the said article with an impervious lining before filling the said container through its open end, providing the said open end with a bottom having a flange turned towards the outer edge of the said open end, crimping the said outer edge over the said flange and setting the said crimped edge against the said flange.

EDOUARD LOUIS DIOT.
